[57] ABSTRACT

A U-shaped body member having a pair of arms urged apart by spring means and terminating at their lower ends in jaws arranged to clamp the cuffs of trousers therebetween. A link has pivotal connection at one of its ends to one of the arms and pivotal connection at its other end to an over-center latch member pivotally supported on the other arm. The pivot connection of the link with the latch member is off-set from the pivot connection of the latch with its supporting arm. The latch is rotatable between two positions one of which causes the link to spread the jaws and the other position of which comprises an over-center position with the jaws being drawn together in a clamped position on the trousers. The latch member projects laterally from one side of the body member for ready finger engagement, making the hanger readily operable with one hand.

GARMENT HANGER**BACKGROUND OF THE INVENTION**

This invention relates to new and useful improvements in garment hangers.

Garment hangers have heretofore been provided which employ a pair of jaws between which the cuffs of trousers are engaged for hanging the pants upright from the cuffs. Most of these prior hangers utilize a spring connected body member having crossed arms for the jaws whereby the trousers are mounted on the hangers by springing the arms apart, inserting the cuffs between the jaws, and then releasing the arms. In such structures, the grip on the pants is accomplished entirely by the spring force of the body member. In order to mount the pants in place, the operator must spring the body member with one hand while installing the pants with the other hand, and to accomplish an adequate holding force for the pants, the spring effect of the body member must be quite strong. Such makes the hanger hard to operate, and if the spring effect of the body portion is lessened to increase the ease of operation, or if the spring effect becomes weak with use, then the pants are not adequately held in place.

SUMMARY OF THE INVENTION

According to the present invention and forming a primary objective thereof, a garment hanger is provided which is designed to provide ease of operation, particularly an operation which may be effected by one hand, and which at the same time provides a positive grip on the trousers.

A more particular object of the present invention is to provide a garment hanger of the type described employing a U-shaped body member supporting a pair of jaws between which the cuffs of trousers are engaged, and also employing an actuating link between the arms of the U-shaped body member operated by a latch capable of moving the jaws of the body member from a spaced apart position to a clamped position on the trousers.

Another object is to provide a garment hanger of the type described wherein the operating mechanism for opening and closing the jaws, comprising the link and rotatable latch, are readily engaged and operable by one hand, and further to provide in said operating mechanism means to open the jaws wider than their normal open position to receive extra thick garments.

The invention will be better understood and additional objects and advantages will become apparent from the following description.

BRIEF DESCRIPTION OF THE DRAWINGS

FIG. 1 is a side elevational view of a garment hanger embodying features of the present invention;

FIG. 2 is an end view of the hanger, taken from the left of FIG. 1 and showing the hanger closed for engaging the cuffs of a pair of pants;

FIG. 3 is a view similar to FIG. 2 but showing the hanger open; and

FIG. 4 is a sectional view taken on the line 4-4 of FIG. 2.

DETAILED DESCRIPTION OF A PREFERRED EMBODIMENT

With particular reference to the drawings, the garment hanger of the present invention comprises a U-

shaped body member 10 consisting of a pair of arms 12 and a connecting portion 14. It is preferred that the arms be substantially rigid but that the connecting portion 14 be sufficiently flexible or springy throughout its length to permit the arms to move apart and together an amount sufficient to receive and to clamp a pair of trouser cuffs therebetween. A body member constructed of a suitable sheet metal or plastic may possess the inherent requirements.

10 The lower ends of the arms 12 carry a pair of longitudinally extending parallel jaws 16 between which the trouser cuffs are adapted to be clamped for the purpose of supporting the trousers in inverted position. A supporting hook 18 is integrated with the upper end of the body portion 10.

The body member 10, and more particularly the connecting portion 14, is arranged in its formation to hold the jaws 16 normally open as shown in FIG. 3. The mechanism for closing the jaws as shown in FIG. 2 20 comprises a link 20 having a longitudinally disposed pivot connection 22 at one of its ends on one arm. This link has pivotal connection 24 in a bifurcated portion 25 of a latch member 26 in turn having a pivot connection 28 on the other arm, the latter pivot connection 25 also extending longitudinally or in the same direction as the jaws. Both arms 20 have suitable slot means 30 for receiving the link 20 and latch member 26 and permitting operation thereof.

The pivot connection 24 between the link 20 and the 30 latch member 26 is offset or eccentric with relation to the pivot support 28 for the latch member, and with the jaws open, FIG. 3, the connection 24 is located at a point intermediate the arms and above the pivot support 28. For drawing the jaws together, the latch member 26 is rotated counterclockwise as viewed in FIGS.

2 and 3 to a position wherein the pivot connection 24 is disposed outside of the one arm, FIG. 2, and is over center relative to the pivot support 28. Such over-center position of the pivot connection 24 holds the jaw 35 members positively together.

Latch member 26 has a contoured edge 32 opposite from pivot support 28 to provide gripping projections 34 for assisting the operator in rotating the latch, the latch being rotated between its two positions by suitable finger engagement with the projections 34. Secured on the outer side of one of the arms 12 and extending over the pivot connection 22 is a finger abutment 36. This abutment allows the operator to hook one finger thereunder and facilitate operation of the latch member 26 by means of other fingers on the same hand. The device is thus readily operable by a single hand.

According to the present invention a pair of pants is 55 readily mounted on the hanger first by releasing the latch 26 to the FIG. 3 position to open the jaws, then placing the pants cuffs between the jaws, and then rotating the latch to its over-center position. As stated, the jaws can be opened and closed with a single hand, thus allowing the other hand to suitably manipulate the trouser cuffs when installing or removing the trousers. Since the link connection between the two arms comprises a direct rather than a spring connection, a positive grip will be obtained on the trousers.

60 It is noted in FIG. 3 that in the released rest position of the latch member 26, an imaginary line extending through the two pivot connections 28 and 24 is angled upwardly rather than being directed straight across to-

ward the other arm. Thus, the arms can be spread farther than their normal spring open position by rotating the latch member 26 clockwise past its released rest position and garments of extra thickness can be inserted between the jaws.

It is to be understood that the form of my invention herein shown and described is to be taken as a preferred example of the same and that various changes in the shape, size and arrangement of parts may be resorted to without departing from the spirit of my invention, or the scope of the subjoined claims.

Having thus described my invention, I claim:

1. A garment hanger comprising:
  - a. a U-shaped body member having a pair of arms and a springy connecting portion therefor normally urging the arms apart,
  - b. jaw means on said arms arranged to receive a garment portion therebetween for clamping and holding the garment,
  - c. a laterally extending link pivotally connected at 20 one of its ends to one of said arms,
  - d. an over-center latch member pivotally connected to the other of said arms and having a finger-engaging portion projecting laterally outward from said arm for finger engagement by an operator,
  - e. means pivotally connecting the other end of said

5

link to said latch member,

f. said latch member being rotatable between a released position and an over-center locked position, the movement of said latch member to its released position driving said link and said one arm outwardly from the arm on which the latch member is supported to spread the arms apart to receive a garment between the jaws and the movement of said latch member to its over-center locked position pulling the link and said one arm toward the arm on which the latch member is supported to clamp the jaws together and hold a garment therebetween,

g. and finger abutment means on the outside of the arm to which said link is pivotally connected facilitating anchoring one finger thereagainst upon engaging said latch member with another finger of the same hand, thus providing a clamping garment hanger which is operable between the released and locked positions of said latch member by one hand.

2. The garment hanger of claim 1 wherein said latch member is manually rotatable beyond its released position to drive the arms apart farther than the normal spring open position thereof.
